MALVIN LICHTER, OF NEW YORK, N. Y., ASSIGNOR TO THE STICKLESS CORPORATION, A CORPORATION OF NEW YORK

HAND FAN

Application filed August 14, 1929. Serial No. 385,939.

My invention relates to hand fans of the type in which sheet material is used, my more particular purpose being to improve the quality of the fan and lengthen the life time thereof, and in so doing to economize to some extent in the use of the material.

More particularly stated, I seek to produce a fan in which is incorporated a cardboard blank and a brace rod, these parts being so formed and arranged as to distribute to good advantage the principal stresses to which a fan of this type are usually subjected.

I seek to so form certain portions of the blank as to improve the reinforcing effect of these portions of the blank relatively to the blade of the fan, and also to improve the reinforcing effect of the brace rod used in connection with the blank, and concealed between the blank and the adjacent portion of the fan blade.

Reference is made to the accompanying drawings forming a part of this specification, and in which like reference characters indicate like parts throughout the several figures.

Figure 1 is a front elevation of my improved fan, a portion of the handle being shown as broken away.

Figure 2 is a section on the line 2—2 of Figure 1, looking in the direction indicated by the arrows.

Figure 3 is a section on the line 3—3 of Figure 1, looking in the direction indicated by the arrows.

The fan blade is shown at 4, and in this instance is made of cardboard and substantially circular in form.

The blade 4 is provided with an extending portion 5, integral therewith and having a profile suitable for a handle member.

Mounted upon the fan blade 4, and secured thereto as by means of an adhesive, is a reinforcing blank 6. The main portion of the reinforcing blank overlies the main portion of the blade and includes a pair of arms 7, 7 which extend obliquely upwardly and away from each other along the surface of the blade. The reinforcing blank is formed also with a handle portion 8 which is disposed to mate the handle portion 5 of the blade.

The reinforcing blank 6 is further provided with a projecting tongue 9, integral with it and projecting upwardly between the arms 7, 7.

This projecting tongue 9 is provided with a pair of straight edges 10, 10, which are inclined and meet together at a point midway between the arms 7, 7, as may be understood from Figure 1.

The reinforcing blank is provided at the lower end of its handle portion with a downwardly projecting tongue 11, integral with it and somewhat like the tongue 9 above described. The tongue 11 is bounded in part by a pair of straight edges 12, 12 which are inclined relatively to each other, as indicated at the bottom of Figure 1.

A brace rod 13, which in this instance is simply a stiff wire, is located centrally between the reinforcing blank 6 and the underlying portions of the blade 4 and its handle portion 5.

The purpose of the brace rod 13 is to strengthen the handle of the fan, as well as the connection between the main and handle portions of the fan, in which it is thus incorporated and concealed, and to distribute certain stresses, as hereinafter described.

As the ends of the brace rod 13 extend out to the points of the tongues 9 and 11, the reinforcing effect of the brace rod is carried out to the two outer ends of the tongues 9 and 11. Thus the strengthening effect of the brace rod is very effectively localized.

In practice the reinforcing blank 6 and the blade 4, with the brace rod 13 between them, are pressed together very tightly and made to adhere, and under such conditions as to form a pair of ribs 14 and 15, on opposite sides of the fan.

The two extending portions 5 and 8, and a portion of the brace rod 13 secured firmly between them in the manner above described, together constitute a very practical handle.

I find that the tongues 9 and 11, reinforced as above described by the two end portions of the brace rod 5, confer upon the fan as a whole unusual strength, combined with a fair amount of flexibility.

The effect of the tongue 9 is to enable the

brace rod 13 to be made a little longer, other factors being equal, than would ordinarily be the case. This increased length of the brace rod, coupled with the extra length of the blank as measured along the brace rod and due to the addition of the tongue 9, strengthens the fan blade in the region between the two arms 7, 7. The brace rod and the tongue 9 both project upwardly toward the tip of the fan blade, that is toward the portion of the fan blade which is furthest from the handle portion of the blade, and the arms 7, 7 also, considered collectively, projecting upwardly toward the tip of the blade, but the arms project relatively further upwardly than the tongue and rod. This effectually distributes the reinforcing effect upon the blade, and thus lessens the tendency for the blade to bend abruptly in any one place or along any single proximate line. Because of this fact, whenever the fan blade is slightly bent back and forth, under conditions of actual use, its curvature is less pronounced and is far more even and symmetrical than would usually be the case.

My improved fan is braced, not only by the two arms 7, 7 but also by the tongue 9, and is thus strengthened at three different areas.

This means that the normal and usual bending stresses of the fan blade are limited and controlled from three distinct centers, namely, from the extremities of the arms 7, 7 and from the point of the tongue 9. Not only that, but these three centers are disposed slightly out of alignment, so that any bending of the fan blade in this immediate region is well distributed, the stresses being as far as practicable equally distributed and diffused throughout the entire surface of the fan blade.

The net result is that in the practical use of the finished fan the bending of the fan blade, from the group of three centers out to the tip of the fan blade, is such that the curvature of the blade is substantially uniform, and this is true whether the blade be bent but slightly or to a greater extent, depending on how the fan is used.

In other words, whether the fan be used gently or vigorously will determine the extent to which the blade will flex, and will thus determine its degree of curvature; but whether its curvature be much or little, the curvature will always be substantially uniform throughout the blade.

For the reasons above stated, the life time of the fan is very much prolonged. Not only is the blade less liable to break, but its different parts are less liable to work loose from each other; and generally speaking, the use of the fan is rendered much more satisfactory.

I attribute these advantages mainly if not altogether to the addition of the tongue 9, and the consequent lengthening of the brace rod.

The tongue 11 acts in a somewhat different manner. Like the tongue 9 it conceals the adjacent end portion of the brace rod 11, but it also strengthens the handle completely out to the end thereof. Its bracing effect appears to be somewhat better localized by virtue of the form of the edges 12.

By making the edges 12, 12 substantially straight, so as to provide the tongue 11, the handle members 5 and 8 are rendered less likely to split away from each other while the fan is in use.

I do not limit myself to the precise construction shown in the drawings and above described, as variations may be made therein without departing from my invention, the scope of which is commensurate with my claims.

Having thus described my invention, what I claim as new and desire to secure by Letters Patent is as follows:—

1. A hand fan comprising a blade made of sheet material and provided with an extending portion integral with it, said extending portion being fashioned as a handle member, a blank made of sheet material and provided with a portion serving as a handle member and with a tongue extending from said last mentioned portion, said blank being separate from said blade and secured thereto so that the handle member of the blank is substantially in registry with the handle member of the blade, and a brace rod located between the two handle members and extending along said blade to the end of said tongue and terminating flush with said end of said tongue.

2. A hand fan comprising a blade made of sheet material and having an extending portion integral with it and fashioned as a handle member, a blank made of sheet material and provided with a portion serving as a handle member and with a pair of tongues integral with it and extending from it in opposite directions, said blank being separate from said blade and secured thereto so that the handle member of the blank is substantially in registry with the handle member of the blade, and a brace rod located between the two handle members and extending from the outer end of one tongue to the outer end of the other tongue, said brace rod terminating flush with the outer ends of said tongues.

3. A hand fan comprising a blade made of sheet material and having an extending portion integral with it and fashioned as a handle member, a blank made of sheet material and provided with a pair of arms and with a tongue located between said arms, said arms and tongues being integral with the handle member of the blank, said blank being separate from said blade and secured thereto in such relative position that the handle member of the blank is substantially in registry with the handle member of the blade, and a brace rod located between the two handle

members and extending therefrom to the end of said tongue, and terminating flush therewith.

4. A hand fan comprising a blade of sheet material, said blade having an extending portion integral with it and fashioned as a handle member, a blank made of sheet material and provided with a handle member and with a pair of arms, and also with a pair of tongues located at opposite extremities of the blank and extending therefrom in opposite directions, the arms and tongues of the blank being integral with the handle member thereof, said blank being separate from said blade and secured thereto in such relative position that the handle member of the blank is substantially in registry with the handle member of the blade, and a brace rod located between the two handle members and extending from the end of one of said tongues to the end of the other tongue, said brace rod terminating substantially flush with the edges of said tongues.

5. A hand fan comprising a blade made of sheet material and having a main portion and an integral extending portion fashioned as a handle projecting edgewise from the main portion, a blank made of sheet material formed separate from the blade and having a main portion, an integral tongue portion and an integral handle portion, the main portion of the blank overlying the main portion of the blade and secured thereto, the handle portion overlying the handle portion of the blade and secured thereto, the blank thus serving to reinforce the main and handle portions of the blade, a brace rod interposed between the handle portions of the blank and blade extending longitudinally of said handle portions and continuing at one end across a part of the main portion of the blade, and the tongue portion of the blank extending to overlie and conceal the extending end portion of said brace rod.

45 6. A hand fan comprising a blade made of sheet material and having a main portion and an integral extending portion fashioned as a handle projecting edgewise from the main portion, a blank made of sheet material formed separate from the blade and having a main portion, an integral tongue portion and an integral handle portion, the handle portion overlying the handle portion of the blade and secured thereto, the main portion of the blank being shaped to constitute a pair of arms diverging upwardly and outwardly from the handle portion in opposite directions across portions of the surface of the main portion of the blade and being secured thereto, the blank thus serving to reinforce the main and handle portions of the blade, the tongue portion of the blank projecting therefrom upwardly along the surface of the main portion of the blade at a location between said arms and being of less length than

said arms, and a brace rod interposed between the handle portions of the blank and blade extending longitudinally of said handle portions and continuing at one end across a part of the main portion of the blade and along 70 said tongue and terminating beneath said tongue.

7. A hand fan comprising a blade made of sheet material and having a main portion and an integral extending portion fashioned as 75 a handle projecting edgewise from the main portion, a blank made of sheet material formed separate from the blade and being secured thereto so as to strengthen the blade in the region of the blade handle, said blank 80 having a portion overlying the handle portion of the blade and secured thereto and another portion continuing upwardly onto the surface of the main portion of the blade and secured thereto, said upwardly continuing 85 portion of the blade being formed with a plurality of spaced extensions projecting to different distances upwardly therefrom toward the tip of the blade, and a brace rod interposed between the handle portions of the 90 blank and blade extending longitudinally of said handle portions and continuing at one end across a part of the main portion of the blade and extending along and terminating beneath one of said extensions. 95

Signed at New York city, in the county of Bronx and State of New York, this 3rd day of August, 1929.
